UNITED STATES PATENT OFFICE.

CHARLES WILLIAM LAWSON, OF WATERBURY, CONNECTICUT.

FRAME-CLAMP.

No. 840,777.

Specification of Letters Patent.

Patented Jan. 8, 1907.

Application filed April 20, 1906. Serial No. 312,843.

To all whom it may concern:

Be it known that I, CHARLES WILLIAM LAWSON, a citizen of the United States, residing at Waterbury, in the county of New Haven and State of Connecticut, have invented certain new and useful Improvements in Frame-Clamps, of which the following is a specification, such as will enable those skilled in the art to which it appertains to make and use the same.

This invention relates to clamp devices for use in making mitered frames, such as picture-frames, sash-frames, and any other frames of this class; and the object thereof is to provide an improved clamp device for this purpose which is simple in construction and operation and by means of which a picture or similar frame of any desired size may be conveniently held and clamped for the purpose of securing the parts thereof together.

The invention is fully disclosed in the following specification, of which the accompanying drawings form a part, in which the separate parts of my improvement are designated by suitable reference characters in each of the views, and in which—

Figure 1 is a plan view of my improved clamp device, and Fig. 2 a section on the line 2 2 of Fig. 1 and showing the clamp device mounted on a rotatable table.

In the practice of my invention I provide two central block members a , each of which comprises a bottom portion a^2 and top portion a^3 , and the top portions a^3 are preferably of greater dimensions than the bottom portions a^2 .

The blocks *a* are mounted between parallel side guides *b*, formed integrally with or 40 rigidly secured to a transverse bottom member *b*², and the blocks *a* are provided with side grooves *a*⁴, and the side guides *b* are provided with corresponding longitudinal ribs *b*³, which fit in said grooves, and said ribs 45 and grooves may be circular in cross-section, as shown at the left-hand side of Fig. 2, or angular in cross-section, as shown at the right-hand side of Fig. 2. Passing through the blocks *a* is a screw *c*, the separate ends 50 portions of which are provided with reverse threads, and by turning said screw the blocks *a* may be drawn together or forced apart, according to the direction in which said screw is turned.

55 Pivoted to the tops of the blocks *a* or to the tops of the table portions thereof and

preferably adjacent to the adjacent edges thereof are arms d , said arms being arranged in pairs and each block being provided with one pair, and the blocks a or the table portions thereof are provided with segmental or circular slots or grooves a^5 , through which are passed bolts d^2 , which also pass through longitudinal slots or openings d^3 in the arms d and are provided with thumb-nuts d^4 , and by means of this construction the arms d may be swung in a horizontal plane and adjusted to any desired position and secured in said position. The arms d are also provided with angular clamps e , which are connected with said arms by bolts e^2 , which are also passed through slots d^3 in the arms d and provided with thumb-nuts e^3 , by means of which said clamps may be adjusted to any desired point on the arms d . The clamps e are provided with separate arms separated by an angle of ninety degrees, and each arm is provided with a head e^4 .

In practice the device may be mounted on any suitable support f , as shown in Fig. 2, 80 and connected therewith by means of a screw f^2 passed through the transverse bottom member b^2 , and whenever it is desired to make a frame or secure the separate parts of a frame together the frame members are 85 placed on the clamps e , as shown at g , the arms d being first properly adjusted, after which the screw c is turned so as to force the blocks a together, and in this operation the separate parts of the frame are securely 90 clamped together, as shown in Fig. 1, and may be nailed together by means of nails h , which are shown in Fig. 1 in position for driving. The separate parts of the frame may, however, be secured together by gluing or in 95 any desired manner, and it will be apparent that my improved clamp-frame may be employed in the making of frames of any desired size and the separate parts of the clamps e may be of any preferred length. 100

It will be understood, of course, that the transverse bottom member b^2 may be of any preferred size, width, or construction, all that is necessary in this connection being to provide side guides b rigidly connected by a transverse member, whereby the said side guides form a firm support for the blocks a , which are held thereby and between which said blocks are movable. 105

My improved clamp device is simple in construction and comparatively inexpensive, and it will be apparent that the same may be

employed when making mitered or similar frames of any kind or class.

Having fully described my invention, what I claim as new, and desire to secure by Letters Patent, is—

A clamp of the class described, comprising a base member provided with parallel side guides which extend above the same, blocks movable between said guides, a screw passed horizontally through said blocks and in the plane of said guides and provided at its opposite ends with reversed threads, said blocks being provided with bores which are correspondingly threaded, whereby the turning of said screws will force said blocks apart or draw them together, a pair of arms pivoted to the top of each of said blocks and near the adjacent side faces thereof, and said arms

being adapted to swing in a horizontal plane above said blocks, rotatable clamps adjustably connected with said arms and adapted to hold a frame in a plane above said arms, said blocks being also provided with segmental slots and said arms with headed bolts which are passed therethrough and provided with thumb-nuts, and means for pivoting said base on a support.

In testimony that I claim the foregoing as my invention I have signed my name, in presence of the subscribing witnesses, this 14th day of April, 1906.

CHARLES WILLIAM LAWSON.
